UNITED STATES PATENT OFFICE.

VERNON L. ELWELL, OF LEETON, MISSOURI.

CLOSURE ARRANGEMENT FOR CONTAINERS.

Application filed November 16, 1922. Serial No. 601,297.

To all whom it may concern:

Be it known that I, VERNON L. ELWELL, a citizen of the United States, residing at Leeton, in the county of Johnson and State of Missouri, have invented certain new and useful Improvements in a Closure Arrangement for Containers, of which the following is a specification.

This invention relates to improvements in closure arrangements for receptacles.

The primary object of this invention is the provision of an improved closure arrangement for receptacles ordinarily adapted for containing liquids, whereby a leak proof connection intermediate the closure arrangement and receptacle may be established in facile manner.

A further object of this invention is the provision of an improved receptacle for receiving liquid, such as cream, milk, and the like, embodying a novel type of closure member, and an improved construction to permit quick assemblage and detachment of the closure member on the receptacle to provide an absolutely leak proof joint which cannot become accidentally detached.

Other objects and advantages of this invention will be apparent during the course of the following detailed description.

30 In the accompanying drawing, forming a part of this specification, and wherein similar reference characters designate corresponding parts throughout the several views.

Figure 1 is a side elevation of the improved receptacle, showing the various details thereof in detached relation.

Fig. 2 is an enlarged fragmentary transverse cross sectional view, taken at the junction of the closure and receptacle body portions, to illustrate the manner of connection thereof.

Fig. 3 is a transverse cross sectional view taken substantially on the line 3—3 of Figure 1.

Fig. 4 is a top plan view of the improved receptacle.

Fig. 5 is a fragmentary cross sectional view, showing the manner in which the closure member or lid of the improved device is assembled to the body portion of a receptacle used in conjunction therewith.

In the drawing, wherein for the purpose of illustration is shown but the preferred embodiment of this invention, the letter A generally designates the improved container

which may include the receptacle or body portion B, and closure lid C.

Referring to the receptacle B, the same is preferably of cylindrical formation, and may be of any approved material providing 60 the beaded lower marginal edge 10. The upper portion of the receptacle body 11 is rolled outwardly to provide the annular bead or roll portion 12 defining the annular passageway 13 therein. Prior to rolling of the 65 upper edge portion 12 of the receptacle body 11, the same is slotted inwardly, so that when the roll or bead 12 is complete certain transverse passageways 14 are provided, extending therethrough, which communicate with 70 the annular passageway 13 provided within said roll 12. A wire ring 15^a or analogous loop shaped member is preferably rolled in the passageway 13 of the bead 12; the same being crimped outwardly at predetermined 75 distances, to provide lugs 15, which when the wire ring or loop 15^a is within the bead passageway 13 extends transversely through the openings 14 in the roll or bead 12, and project exteriorly of the outer periphery or 80 circumferential surface of the bead 12, substantially as is illustrated in the various figures of the drawing. These projecting portions of the lugs 15 are adapted for cooperation with the closure member or lid C in a 85 manner which will be subsequently set forth. In order to prevent any liability of displacement of the lugs 15, and to provide a sanitary construction, the slots or openings 14 in the bead or roll 12, after formation are soldered or otherwise sealed about the extending lugs 15.

Referring to the closure member C, the same is preferably of the same material as the receptacle B, and may be stamped of a 95 single piece of material to provide the top 20 which has the annular upstanding and upwardly diverging flange 21 marginally and annularly formed thereon. A downwardly extending tapered flange 23 is bent 100 from the top edge of the flange 21, and forms therewith an annular inverted V-shaped groove 24 in which a resilient packing ring 25 is adapted for disposition. The annular side 26 of the lid C depends from the tapered flange portion 23, and, in fact, is a continuation thereof; said annular side 26 being upwardly rolled or beaded, as at 27, outwardly thereof. The side flange 26 of the improved lid C is provided with 105 110

out struck portions 30 at spaced intervals, which provide vertical relatively wide passageways 31 extending upwardly from the extreme lower marginal edge 32 of the closure roll or bead 27, and terminating in the upwardly inclining passageways 33 which offset at a greater angle than 90° with respect to the run of the vertical passageways 31.

5 10 In assemblage of the closure member C upon the improved receptacle B, the same is disposed over the upper bead or roll 12 of the receptacle B, so that the vertical passageway 31 of each of the outstruck portions 30 receive the lugs or outstanding portions 15 therein. When the closure member C has been pushed so that the arcuate top edge 35 of the roll 12 just engages the under surface 36 of the resilient packing 25, the 15 20 operator by an angular movement relatively rotates the closure member C upon the receptacle B, so that the lug portions 15 ride upwardly in the inclining passageways 33 of their respective outstruck portions 30.

25 This operation will have the effect of more firmly wedging the resilient packing ring 25 into engagement with the beaded top 12 of the receptacle B to provide an absolutely leak proof connection. Of course, the outstruck portions 30, the grooves provided 30 therein, and the various lugs 15 cooperate as bayonet-joints to effectively retain the lid or closure member C upon the receptacle B against liability of accidental detachment.

35 The provision of the lugs 15, in the manner above described provide a relatively simple, extremely durable, and economical construction, being a particularly desirable arrangement in view of the fact that the 40 lugs 15 necessarily are subject to a shearing action as they ride upwardly in the inclined ways 33, so that the resilient packing ring 25 is placed under considerable compression. The lugs ordinarily cast upon articles in 45 providing bayonet joint arrangements are not durable. The improved means of securing the leak proof connection involving the resilient packing ring 25 cooperating in its V-shaped annular groove and resting 50 upon the arcuate upper edge 35 of the bead or receptacle roll 12, provides a construction which is durable, simple, and easy of access for cleansing purposes. In view of the provision of the bead 12 upon the receptacle

B it is obvious that there need be no undue 55 frictional engagement of contacting surfaces of the receptacle and its cover, and the attaching and leak proof connection is formed principally by the bayonet joints and the packing ring engaging the bead 12. 60

Various changes in the shape, size, and arrangement of parts may be made to the form of invention herein shown and described, without departing from the spirit of this invention or the scope of the claims. 65

I claim:

1. As an article of manufacture a container comprising a body receptacle having the upper edge thereof outwardly rolled to provide an annular passageway therein, said rolled edge being transversely apertured, a wire within said passageway crimped intermediate its ends to provide lugs laterally extending through the apertures of said roll, a lid for said receptacle body providing an annular V-shaped recess upwardly therein adapted to receive the roll of said receptacle, said lid providing an outer depending annular flange having outstruck portions thereon providing bayonet slots 80 adapted to receive the laterally extending lugs on the roll of said body receptacle, and a resilient packing within the V-shaped recess adapted to be clamped upon the roll of said receptacle when the lid is placed on 85 said receptacle with the lugs fitting in the bayonet slots thereof.

2. A container comprising a body open at its upper end, a hoop positioned about the upper end portion of said body and having lugs extending in spaced relation to each other about the hoop, the body being slotted and roller outwardly and downwardly about the hoop with the lugs extending outwardly through the slots, a cover having a central portion for fitting into said body and provided with an upstanding annular flange extending above the body, an annular wall extending downwardly from said flange and having bayonet grooves leading upwardly from its lower edge for receiving said lugs, the space between the upper portions of the flange and wall forming a packing receiving seat, and packing in the seat providing a tight joint 100 when the cover is put in place. 105
